United States Patent

Des. 236,763
Patented Sept. 9, 1975

236,763

HAND-HELD HAIR DRYER OR SIMILAR ARTICLE

Walter C. Anderson, West Redding, Conn., assignor to General Electric Company

Filed Apr. 1, 1974, Ser. No. 457,088

Term of patent 3½ years

Int. Cl. D28—03

U.S. Cl. D86—10 F

FIG. 1.

FIG. 2.

FIG. 3.

FIG. 4.

FIG. 5.

FIG. 6.

FIG. 7.

FIG. 1 is a perspective view of a hand-held hair dryer showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left end elevational view thereof; and FIG. 7 is a right end elevational view thereof.

I claim:

The ornamental design for a hand-held hair dryer or similar article, substantially as shown.
